JAMES S. QUIGG, OF DEWEY, OKLAHOMA

DEVICE FOR REGULATING THE PUMPING PERIODS OF WELLS

Application filed February 25, 1932. Serial No. 595,212.

This invention relates to a device for regulating the pumping periods of wells.

At present oil wells are pumped at the speed of the power plants so that when the well is pumped off or dry the operator must disconnect the well from the power plant and this requires the services of an operator when the well is pumped dry. Furthermore, when a pump is connected with the usual power plant the pumping action is continuous and the well is pumped at too great a rate and frequently at a greater speed than the return of flow of the oil into the well.

An object of the invention is the provision of a device located between the power plant and a pump for automatically cutting off the pump for definite periods so that the well will be pumped at a slower rate and at a rate which will conform to the flow of the oil into the well.

A further object of the invention is the provision of a device intercalated between the power plant and the pump for automatically cutting off the pump at predetermined periods so that it will not require the constant attendance of an operator, particularly at the time that the well is pumped off.

This invention will be best understood from a consideration of the following detailed description, in view of the accompanying drawings forming a part of the specification; nevertheless, it is to be understood that the invention is not confined to the disclosure, being susceptible of such changes and modifications which shall define no material departure from the salient features of the invention as expressed in the appended claims.

In the drawings:

Figure 1 is a side elevation of a device constructed in accordance with the principles of my invention, showing the pumping connection in inoperative position,

Figure 2 is a plan view of the device shown in Figure 1,

Figure 3 is a fragmentary enlarged view of the device for regulating the pump periods,

Figure 4 is a side view in elevation of the device shown in Fig. 1 with the pump operatively connected with the power plant,

Figure 5 is a fragmentary side view in elevation of the controlling device showing the rear face thereof,

Figure 6 is an enlarged fragmentary side view of the controlling device disclosing the position of the parts just before the pump is connected to the power plant, and

Figure 7 is a transverse vertical section taken along the line 7—7 of Figure 1.

Referring more particularly to the drawings, 10 designates a post having its base portion secured in the ground in any approved manner. The upper end of the post is provided with a passage or bearing, as indicated in dotted lines at 11, to receive a reciprocating pumping rod 12. The outer end 13 of this rod is connected in any approved manner with the pump (not shown). The inner end of the rod 12, as shown at 14, is pivotally connected with a pair of plates 15 located at one side of the post 10. These plates at their inner ends are pivotally connected at 16 with a latch bar 17 which is adapted to be periodically reciprocated as will be presently described.

A pair of U-beams 20 are connected at 21 to the post 10. The opposite ends of these beams which are parallel and spaced from each other are connected at 22 to a block 23. This block may be secured in place in any approved manner to the ground or floor of a building. The inner end of the block is located between a pair of ends of the beams 20.

A driving rod 25 is supported by the block 23 and has its outer end 26 connected with a power plant (not shown). Collars 27 and 28 are secured to the driving rod 25 by means of set screws 29 and the distance between these collars determines the travel of a cross head 30 which is provided with a passage 31 through which the driving rod 25 passes.

The inner end of the driving rod is provided with a yoke 32 and this yoke has a bridging portion 33 into which is screwed the inner end of the rod 25. The yoke 32 is bent upwardly, as shown at 32, 34, and is disposed in a plane parallel to the top of the block 23 so that the end 35 of the yoke is

located above the horizontal plane passing through the rod 25.

An oscillating lever 36 is pivotally mounted at 37 on a bracket 38 secured to one of the beams 20, as shown more particularly in Fig. 2. A link 39 connects the upper end of the lever 36 with the upper end of the cross head 30, so that as the cross head is reciprocated the lever will likewise be oscillated.

10 A drum 40 is mounted for rotation upon an axle 41 carried by a bracket 42 secured to one of the beams 20. A second bracket 43 is secured to the other beam and provides a support for the axle 41. The drum is provided 15 with a segmental ratchet wheel 44 adjacent one of the beams 20. A second ratchet wheel 45 is connected to the opposite side of the drum and is adjacent the bracket 42. The ratchet wheels 44 and 45 may be made separately and connected with the drum or may be made integrally with the drum. Since the drum is of less diameter than the ratchet wheels 44 and 45, there will be a space located 20 between said ratchet wheels upon which normally rests the inner end of the latch bar 17. A cam 46 is formed on the drum 40 between the ratchet wheels for a purpose which will be presently explained. The ratchet wheel 45 is provided with a plurality of spaced teeth 25 47 which are adapted to be engaged by a pawl 48 pivotally mounted at 49 on the oscillating lever 36. A master tooth 50 is provided at one end of the series of teeth 47. It will be noted that the top of the bracket 30 42 is curved, as shown at 51, and this curved portion extends slightly above the teeth 47 but below the outer end of the master tooth 50 so that the pawl 48 will ride upon the curved portion 51 of the bracket 42 for a definite period of the movement of the pawl 48.

The pawl 53 is pivotally mounted at 54 upon a standard 55 which is secured to that beam 20 which is located adjacent the ratchet wheel 44. The pawl 53 normally engages the 45 teeth of the ratchet wheel 44 and maintains the drum and the ratchet wheels in a predetermined position until released as will be presently explained.

The ratchet wheel 44 is provided with a 50 series of passages 58 adapted to receive a bolt 59 which will engage at times one of the beams 20 and retain the drum and ratchet wheels in a predetermined position.

The latch bar 17 is provided with a catch 55 60 which is adapted to receive the end 35 of the yoke 32. The outer edge of the catch 60 is provided with a curved face, as shown at 61, in order to facilitate the engagement of the yoke 32 with the catch 60.

60 The operation of my device is as follows: Referring more particularly to Figure 1, it will be seen that the catch 60 is located between the ratchet wheels 44 and 45 and resting upon the drum 40 while the outer end of 65 the connecting plates 15 are engaging the

inner face of the post 10. When the power plant has been connected with the driving rod 25, said rod will be reciprocated and the collars 27 and 28 will alternately engage the cross head 30, causing reciprocation of said cross head and likewise of the rod 39. The lever 36 will be oscillated and the pawl 48 will ride over the curved edge 51 of the bracket 42 until it passes beyond the higher point on the curved edge 51 when it will drop into engagement with a tooth 47 of the ratchet wheel 45. Movement of the lever 36 in the direction indicated by the arrow in Fig. 1 will cause the pawl 48 to rotate the ratchet wheel 45 and likewise the drum 40 and the ratchet wheel 44. The movement of the drum and the ratchet wheel will be a step by step method and the length of the curved edge 51 of the bracket 42 will provide for an angular rotation of the drum and ratchet wheels which will be equal to the angular relation between two of the teeth 47 of the ratchet wheels 45. In other words, upon each movement of the lever 36 in a direction indicated by the arrow in Figure 1, pawl 48 will move the ratchet wheel 45 through the space of one tooth. Since the pawl 53 is in engagement with the teeth of the ratchet wheel 44, said pawl will retain the drum and the ratchet wheels in the angular position through which they have been moved by the pawl 48.

When the collar 27 engages the cross head 30 on the return stroke of the driving rod 25, the lever 36 will be moved in the direction opposite that indicated by the arrow in Figure 1. At this time, however, the pumping rod 12 and the latch bar 17 are idle so that at this time the pump is not forcing oil or other liquids from a well.

When the ratchet wheels 44 and 45 and the drum have been moved through a step by step position so that the master tooth 50 will be engaged by the pawl 48, the drum 40 and the ratchet wheels 44 and 45 will be moved through a greater angular distance since the tooth 50 extends above the curved edge 51 of the bracket 42 and therefore will be engaged by the pawl 48 at a point which will be in advance of the engagement of the pawl with the teeth 47 of the ratchet wheel 45. Just about the time, however, that the pawl 48 engages the tooth 50 of the ratchet wheel 45, as shown in Fig. 3, the cam 46 will engage the latch bar 17 and gradually elevate said latch bar until the catch 60 will be moved through the portion 34 of the yoke 32. It will be appreciated, however, that the yoke at this time will be moved towards the drum 40 by the rod 25. When the rod 25 is moved outwardly on the return stroke it will pull the elevated latch bar 17 through the medium of the end 35 of the yoke 32 and the catch 60 and thereby operate the pump rod 12, thus delivering a pumping stroke to the pump.

As the latch bar 17 moves in the direction

indicated by the arrow in Fig. 1, a plate 65 which is secured to the latch bar 17 will move beneath the pawls 48 and 53 and thereby release the pawl 48 from its engagement with 5 the master tooth 50 and the pawl 53 from its engagement with the teeth of the ratchet wheel 44. Since the ratchet wheels and drum are free to move, and the cam member 46 acts as a counterbalance, the counterbalance will 10 move downwardly and rotate the drum and the ratchet wheels to their normal position to be operated by the pawls 48 and 53 without causing operation of the latch bar 17 and the pumping rod 12. 15 The bolt 59 is placed in one of the passages 58 in the ratchet wheel 44 so that as the ratchet wheels and the drums are moved by the weighted cam 46, this bolt will engage one of the beams 20, as shown in Fig. 5, and 20 retain the drum and cam in an operative position. When the cam member 46 moves downwardly, after release of the ratchet wheel from the pawls, the latch bar 17 will be unsupported and it will move downwardly 25 and rest upon the drum 40. The release of the latch 60 from the yoke 32 is also due in part to the fact that as the rod 25 is moved upon its return stroke and the rod 12 is moved outwardly towards the pump, the hinging 30 members 15 will likewise be moved in an opposite direction, as indicated by the arrows in Fig. 1, and will engage the post 10, thereby limiting the outward movement of the latch bar 17. However, the driving rod 25 continues its movement beyond the catch 60 so 35 that the catch will be released from the yoke.

When the latch bar 17 is being moved to the position shown in Fig. 1, the plate 65 will release the pawls 48 and 53 and they will 40 drop to their normal operative position with respect to the ratchet wheels 45 and 44.

It will be seen by this construction that the operation of the pump will be periodic. The duration of rest, however, is determined 45 by the position of the bolt 59 in the passages 58 so that it is possible to shorten or lengthen the time of inactivity of the pump.

The position of the collars 27 and 28 depends upon the annular movement of the 50 lever 36 and such positions may be readily determined during the operation of the device.

I claim:

1. A device for periodically controlling the 55 pumping action of a pump comprising a power driven reciprocating rod provided with a yoke, a latch rod connected with an operating element of a pump and provided with a catch, a drum provided with a cam 60 adapted to engage periodically the latch rod and move the catch into operative relation with the yoke for causing the latch rod to be reciprocated by the power driven rod and the pump to be actuated periodically, the cam 65 providing a weight for the drum tending to

rotate the drum and move the cam to an inoperative position, means for causing rocking of the drum for moving the cam into operative relation with the latch rod, means for retaining the drum and likewise the cam in 70 an operative position temporarily, and means for releasing the retaining means periodically to permit the drum and cam to move to an inoperative position.

2. A device for periodically controlling the 75 pumping action of a pump comprising a power driven reciprocating rod provided with a yoke, a latch-rod connected with an operating element of a pump and provided with a catch, a drum provided with a cam 80 adapted to engage periodically the latch rod and move the catch into operative relation with the yoke for causing the pump to be actuated periodically, means for imparting a rotary step by step movement of the drum and cam so that the cam will move the latch rod to an operative position relative to the yoke, means for retaining the cam in an operative position, means for releasing the cam, and means causing reverse rotation of the 85 drum and for moving the cam to an inoperative position.

3. A device for periodically controlling the 90 pumping action of a pump comprising a power-driven reciprocating rod provided with a yoke, a latch rod connected with an operating element of a pump and provided with a catch, a rotatably mounted cam 95 adapted to move the latch rod to cause the catch to engage the yoke and temporarily operate the pump, means for causing a rotary step by step movement of the cam while the cam is out of operative relation with the latch rod and including means for moving the cam into operative relation with the latch rod, means for retaining the cam in an operative position, a plate carried by the latch rod adapted to engage and move the retaining means out of operative relation with the cam for releasing the cam, the cam forming 100 a weighted element so that said cam will return automatically to a normal inoperative position.

4. A device for periodically controlling the 105 pumping action of a pump comprising a power-driven rod provided with a yoke, said rod being continuously reciprocated, a latch rod connected with an operating element of a pump and provided with a catch, a cam 110 adapted to move the latch rod to cause the catch to engage the yoke and temporarily operate the pump, means for causing a rotary step by step movement of the cam while the cam is out of operative relation with the latch rod and including means for moving the cam 115 into operative relation with the latch rod, means for releasing the cam, and means for causing said cam to move to an inoperative position to release the catch from the yoke.

5. A device for periodically controlling 120

the pumping action of a pump comprising a power-driven rod provided with a yoke, said rod being continuously reciprocated, a latch rod connected with an operating element of a pump and provided with a catch, a cam adapted to move the latch rod to cause the catch to engage the yoke and temporarily operate the pump, ratchet wheels connected to the cam, a pawl pivoted on a fixed support
5 engaging one of the wheels for retaining the same in a predetermined position, a pivotally mounted lever, means connecting said lever with the reciprocating rod for causing oscillation of said lever, a pawl pivoted on the
10 lever and engaging the other ratchet wheel for causing a rotary step by step movement of the cam, means on the last-mentioned ratchet wheel adapted to be engaged by its respective pawl for moving the cam into engaging position with the latch bar, said cam including a weight for returning said cam to an inoperative position when the pawls are released, and means for releasing the pawls.
